UNITED STATES PATENT OFFICE.

CECIL H. STRUPE, OF INDIANAPOLIS, INDIANA, ASSIGNOR TO LEEDY MANUFACTURING COMPANY, OF INDIANAPOLIS, INDIANA, A CORPORATION OF INDIANA.

BANJO-NECK-ADJUSTING MEANS.

Application filed September 24, 1926. Serial No. 137,472.

My invention relates to improvements in banjos and particularly to means for regulating the action thereof.

More specifically my invention relates to means for shifting the end of the neck of the banjo to cause the same to lie in different planes relatively to the plane of the head whereby the distance between the strings and the frets is varied.

For the purpose of disclosing my invention I have illustrated certain embodiments thereof in the accompanying drawings in which

Fig. 1 is a side elevation of a banjo embodying my invention;

Fig. 2 is an enlarged side elevation, partly in section, showing the action regulating means;

Fig. 3 is a detail section on the line 3—3 of Fig. 2;

Fig. 4 is a detail section showing a modification of my invention, and

Fig. 5 is an end view thereof.

In the embodiment illustrated I provide the cylindrical shell 1 which may be of sheet metal and is at its upper and lower ends spun or rolled over to form beads 2 extending within the shell. Within the shell between the beads and abutting against the shell 1 is arranged a wooden band 3. The shell is provided with the usual heads, flesh rings and tension adjusting means therefor (not illustrated however in Fig. 2). Within the shell is mounted a cross bar 4 one end 35 of which (not shown) is firmly attached to the wooden band or shell and the other end 5 of which is adapted to project through the shell and have secured thereto the neck 6 of the banjo. For securing the neck in position the end of the neck is bored out to form an opening 7 which fits over a shoulder 8 on the end of the brace 4. This shoulder is sufficiently wide to make a comparatively snug fit in the bore but is flattened at its top 45 and bottom to provide a clearance between it and the walls of the bore. A dowel pin 9 is secured in the brace 4 and has an extended end 10 projecting in the bore 7 and extending transversely through the neck and

50 the dowel pin 9 is a rocking pin 11 which not only serves to hold the neck against longitudinal movement but also provides a pivot point on which the neck may be rocked. Extending upwardly from the bottom of the neck is an adjusting screw 12

passing through a nut 13 preferably seated in the wood of the neck. The upper end of this screw bears against the forward end of the dowel pin 9. By this arrangement the adjustment of the screw up or down will cause the neck to rock on the pin 11 and thereby change the plane of the outer end of the neck so that the clearance of the strings from the frets or fret board of the neck may be regulated.

In Figs. 4 and 5 I have illustrated a modification of the invention illustrated in Fig. 2 wherein I provide a mounting pin 14 which takes into the recess 7 in the neck in the same manner as the pin 9 and is secured to the neck by the transversely rocking pin 15 similar to the rocking pin 11. The neck is adjusted by means of an adjusting screw 16 similar to the adjusting screw 12. In this form however the pin 14 is secured directly to the shell and to this end the base of the pin 14 is provided with a squared portion 17 fitting in a squared opening in the shell and this base is provided with a plurality of ears 18 fitting flatly against the inner face of the shell and secured thereto by suitable screws passing through screw openings 19 and into the shell.

I claim as my invention:

1. In a banjo, the combination with a shell, of a cross brace projecting beyond the shell mounted within said shell, an extension for said cross brace, a neck having a socket receiving said extension and pivotally connected thereto and means for rocking said neck on said pivot for raising or lowering the outer end of the neck to thereby raise or lower the strings of the banjo with relation to the fret board of the neck.

2. In a banjo, the combination with a shell, of a cross brace mounted within said shell, a neck, an extension of said cross brace projecting into said neck, a transverse pin passing through said neck and extension forming a pivot member for the neck and an adjusting screw extending through the neck at an angle to the plane of the pin and engaging the end of said extension.

3. In a banjo, the combination with a shell, of a cross brace mounted therein, a dowel pin mounted in said cross brace, a neck having a recess for the reception of the opposite end of said dowel pin, a transverse pivot pin extending through said neck and dowel pin and an adjusting screw.

screw in said neck at an angle to said dowel pin and bearing upon the end of the dowel pin projecting into the neck.

4. In a banjo the combination with a shell, of a neck and means for securing the neck to the shell including a projecting pin mounted on the shell and extending into a socketed recess in the neck, a transversely extending rocking pin passing through said neck and projection and a set screw in said neck adapted to engage said projection beyond 15 said pin for rocking the neck on said pin.

5. In a banjo, the combination with a shell, of a neck and means for connecting 10

said neck with said shell comprising a projection extending beyond the periphery of 15 the shell and into a socketed recess in the end of the neck, a transversely extending rocking pin passing through said neck and projection and a set screw in said neck adapted to engage said projection beyond 20 said pin for rocking the neck on said pin.

In witness whereof, I CECIL H. STRUPE, have hereunto set my hand at Indianapolis, Indiana, this 20th day of September, A. D. one thousand nine hundred and twenty-six.

CECIL H. STRUPE.
